UNITED STATES PATENT OFFICE.

FELIX GOTTSCHALK, OF HILTON, NEW JERSEY.

TRANSMITTER-CELL.

1,245,218.

Specification of Letters Patent.

Patented Nov. 6, 1917.

Application filed March 31, 1916. Serial No. 87,967.

To all whom it may concern:

Be it known that I, FELIX GOTTSCHALK, a citizen of the United States, residing at Hilton, in the county of Essex and State of New Jersey, have invented certain new and useful Improvements in Transmitter-Cells, of which the following is a specification, reference being had to the accompanying drawing.

10 My invention relates to transmitter cells. In telephone transmitters and those of similar types embodying a variable resistance medium and electrodes, there is a space between the side of the electrode attached to the vibrating diaphragm and the walls of the chamber inclosing the resistance medium. The coarse grain or shot particles of the resistance medium must not fill the entire enclosure of the chamber to avoid packing and 15 to allow free movement of the vibrating electrode, and, as the transmitter is only operative when held with the vibrating diaphragm substantially vertical, these grains often find lodgment between the sides of the vibrating 20 diaphragm and the walls of the chamber, and have a tendency to make the instrument "noisy" and frequently cause packing.

25 My improvement not only confines the variable resistance medium within the closed chamber, but further confines it to contact only with the face of the vibrating electrode without interfering with the free movement thereof.

Another improvement is the provision of 30 free air spaces directly underneath the vibrating diaphragm and within the cell, thereby reducing the air compression therein to a minimum.

In the accompanying drawings, Figure 1 35 shows a transmitter cell with the granular resistance medium confined to contact only with the face of the vibrating electrode. Fig. 2 is the top view of my improved cell closure showing the spaces therein, whereby 40 the air compression within the cell is reduced.

Like figures of reference denote the same parts wherever they are shown.

45 1 denotes a free vibrating diaphragm under the periphery of which may be placed a suitable insulating packing 2. Carried by said diaphragm is the movable electrode 3. The cell member is shown at 4, in which is

the chamber 5 containing a suitable variable resistance medium and the rear electrode 6. 55

Surrounding the movable electrode 3 but not touching the same is the member 7, preferably of insulating material; a sufficient space is permitted, to allow free movement of the front electrode. 60

The member 7 has an annular ring portion indicated at 8 which is connected by radial arms, 9, 10, 11, and 12, to the outer ring, thereby forming the air spaces, 13, 14, 15, and 16. By referring to Fig. 1, it will now 65 be seen that these spaces located directly under the diaphragm, reduce the compression that would otherwise exist if said air spaces were not present.

As the operation of transmitter cells are 70 well understood by those skilled in the art and as the construction herein described does not change the method of operation in any way, I do not describe same here. This cell may be used with any suitable form of transmitter. 75

Having thus described my invention I claim:

1. In a transmitter cell, a member forming a chamber, a resistance medium within said chamber, a vibratory member forming a complete closure for said chamber, an electrode secured to the under side of said vibratory member and adapted to act upon said resistance medium and means surrounding 85 said electrode and secured to said cell member whereby said resistance medium is confined in contact to the flat surface of said electrode.

2. In a transmitter cell, a member forming a chamber, an electrode in said chamber covering the entire bottom thereof, a resistance medium in said chamber, a diaphragm completely closing said chamber, an electrode of less diameter than said chamber 95 secured to the under side of said diaphragm, and a ring secured to said chamber underneath said diaphragm and about said last electrode, whereby said resistance medium is confined in contact to the flat face of said last electrode. 100

3. In a transmitter, a member forming a chamber, an electrode therein, a resistance medium in said chamber, a diaphragm closing said chamber and carrying an electrode 105 projecting therein, and a member secured to

said first member forming a ring about said last electrode said member having radial apertures forming air spaces between said first member and diaphragm, substantially 5 as described.

4. In a transmitter, an electrode, a cell cover comprising a member having a central aperture slightly larger than the electrode, a rim about said aperture, an outer rim, 10 radial arms extending outwardly from said

first rim and joined to said outer rim, thereby forming spaces between said arms, and means for securing said outer rim to a cell body, substantially as described.

In testimony whereof I hereunto affix my 15 signature in the presence of two witnesses.

FELIX GOTTSCHALK.

Witnesses:

JOHN C. GORDON,
EDMUND R. DODGE.
